ROBERT C. PAULY, OF CINCINNATI, OHIO, ASSIGNOR TO THE AMERICAN LAUNDRY MACHINERY COMPANY, OF CINCINNATI, OHIO, A CORPORATION OF OHIO

PRESSING MACHINE

Application filed May 11, 1929. Serial No. 362,221.

This invention relates to improvements in machines for pressing fabrics, such as wearing apparel, and has particular relation to improvements in those parts of such machines which control the closing thereof for the pressing operation and the opening thereof. Such a machine is closed by bringing about pressing engagement of the two pressing members of the machine and is opened by bringing about disengagement or separation of said members, sufficient separation being preferably produced to provide convenient access to the lower pressing member for arranging thereon the work to be pressed. One or both of the pressing members may be movable, although these machines usually have the lower pressing member stationary and the upper pressing member movable into and out of engagement therewith.

One of the objects of the present invention is the provision of such a fabric pressing machine having improved mechanism for controlling the closing and opening of the press, said control mechanism including a single inlet valve having a normal tendency to close and a single outlet or exhaust valve also having a normal tendency to close but held in open condition, when the press is open, by maintaining means provided therefor.

A further object of the present invention is the provision of such a pressing machine having improved control mechanism as above specified, with said mechanism requiring for its operation to effect closing of the press, the use of both of the operator's hands and further requiring the operation of the inlet valve prior to the operation of the outlet or exhaust valve. Such sequential operation of the valves is insured by a valve interlock which latches the outlet or exhaust valve against operator operation when the press is open, said latch being releasable by operation of the inlet valve.

A further object of the invention is the provision of such a pressing machine having improved control mechanism as above specified, with said mechanism including two separate maintaining means, one for the

inlet valve and one for the outlet valve, both of said maintaining means being of mechanical character and being operable by closing and opening movements of the press. The maintaining means for the inlet valve holds said valve closed during the pressing operation but does not become effective for this purpose until the pressing members have been brought into engagement or substantially so. The maintaining means for the outlet valve holds said valve open when the press is open and remains effective to bring about opening of the outlet valve until the pressing members have been brought into engagement or substantially so. When the press is open, the inlet valve remains closed because it is a normally closed valve and when the press is closed, the outlet or exhaust valve remains closed because it also is a normally closed valve.

A further object of the invention is the provision of such a pressing machine having improved control mechanism as above specified, with the valve interlock of said mechanism effective to cause, when it is desired to open the press, the closing of the inlet valve prior to the opening of the outlet or exhaust valve, such sequential valve operation being accomplished and the press opened by the use of but one hand of the operator—her left hand for actuating the operating means for the outlet or exhaust valve.

Further objects of the invention are in part obvious and in part will appear more in detail hereinafter.

In the accompanying drawings, Fig. 1 is an elevation of the right side of a pressing machine embodying the present invention, part of the frame of the machine being broken away to show interior construction; Fig. 2 is an elevation of the left side of the machine; Fig. 3 is a schematic view of the mechanism for controlling the press operations; Fig. 4 is a detail sectional view of some parts of the control mechanism of the machine, the view being on the lines 4—4, Figs. 1 and 2; Fig. 5 is a detail view of the inlet valve of the control mechanism, said valve being in open

position due to operator operation but with the press still open; Fig. 6 is a similar view but showing said inlet valve closed, this being the normal position of these parts when the press is open; Fig. 7 is a similar view, but showing the inlet valve held in open position during the pressing operation by maintaining means provided therefor; Fig. 8 is a detail view of the outlet valve in the open position which it occupies when the press is open, the position of the latching means for said outlet valve, after actuation of the inlet valve, being shown in dash-dot lines; Fig. 9 is a detail view of the outlet valve after it has been closed by operator operation; and Fig. 10 is a detail view showing the outlet valve in the closed position which it occupies during the pressing operation, the maintaining means therefor being now ineffective to open said valve.

The pressing machine illustrated in the drawings includes a suitable frame 1 having a pedestal 2 on which is mounted a lower pressing member 3. Said frame is also provided with a rearwardly and upwardly extending arm 4 on the upper end of which is pivoted at 5 a head lever 6 carrying at its forward end an upper pressing member 7. Connected to the rear end portion of said head lever are the upper ends of two springs 8 having their lower ends connected to a pin 17 mounted in the machine frame, said springs tending to move said head lever, and hence the upper pressing member 7, in a clockwise direction, Fig. 1, and thereby serving to open the press and to thereafter maintain the press open with the upper pressing member separated from the lower pressing member a sufficient amount to enable convenient access to be had to said lower pressing member for arranging thereon the work to be pressed.

The means for moving the upper pressing member into and out of pressing engagement with the lower pressing member includes a toggle comprising an upper member 10 and a lower member 11, the upper end of said lower member being connected to the lower end of the upper member by a pin 12. The upper end of the upper toggle member is connected at 13 to the rear end portion of the head lever 6 while the lower end of the lower toggle member 11 is connected at 15 to the rear end of a pressure lever 16 pivoted at 17 to the frame of the machine. The pressure lever 16 is provided between its pivot point and its front end with an upwardly extending arm 19 carrying a roller 20 at its upper end. This roller is movable in a cam slot 21 of a cam lever 22 having its front end pivoted at 23 to the machine frame and its rear end connected at 24 to the forward end of a connecting rod 25 having its rear end connected to the toggle knuckle pin 12.

The means for operating the pressure lever 16 to effect straightening of the toggle and

hence closing of the press includes a cylinder 30 having its lower end secured at 31 to the machine frame and having movable therein a piston 32 mounted on the upper end of a piston rod 33. The lower end of said piston rod is provided with a roller 34 movable in a slot 35 in the front end of the pressure lever 16, all as clearly shown in Fig. 1.

Either steam or air is suitable for moving the piston 32 in the cylinder 30 to effect closing of the press. The means for supplying such a fluid to said cylinder includes a supply pipe 40, Fig. 3, having its delivery end connected to the supply side of the casing 41 of an inlet valve 42. The flow of fluid through said inlet valve is controlled by a valve member 43 normally held closed against its seat by a spring 44. Connected to the discharge side of this inlet valve casing is one end of a pipe 45 having its other end connected to the supply side of a needle valve 46. Connected to the discharge side of said needle valve is one end of a pipe 49 having its other end connected to a T 50. Connected to this T is one end of a pipe 51 having its other end connected to an elbow 52 in turn connected to one end of a pipe 53 having its other end connected to the upper end of the cylinder 30.

To close the press, the inlet valve 42 is opened and an outlet or exhaust valve 64 hereinafter described is closed. Steam or air from supply pipe 40 is now free to flow through the inlet valve to the cylinder 30 and the piston 32 in said cylinder is moved downwardly under the pressure of said steam or air. The pressure lever 16 is moved by the piston rod 33 in a counter-clockwise direction, Fig. 1, about its pivot 17 and the downward movement of the roller 20 of the lever arm 19 actuates the cam lever 22 in a clockwise direction to produce forward movement of the connecting rod 25. Such forward movement of the connecting rod straightens the toggle formed by members 10 and 11 and causes the head lever 6 to move about its pivot 5 in a counter-clockwise direction, thereby bringing the upper pressing member 7 down into engagement with the lower stationary pressing member 3. At the same time, the toggle members 10 and 11 are raised by the counter-clockwise movement of the pressure lever 16, which further elevates the rear end portion of the head lever 6 and causes the pressing member 7 on the forward end of said head lever to engage the lower pressing member 3 with considerable pressure, amply sufficient to properly press the work on said lower pressing member.

In order to effect opening of the press, the fluid supplied to the cylinder 30 for the press closing operation must be exhausted therefrom. For such purpose, a pipe 60 (Fig. 3) has one of its ends connected to the

T 50 for receiving from the cylinder 30, by means of T 50, pipe 51, elbow 52 and pipe 53, the fluid to be exhausted from said cylinder. The other end of pipe 60 is connected 5 to one end of an elbow 61 having its other end connected to one end of a pipe 62. The other end of pipe 62 is connected to the supply side of the casing 63 of an outlet or exhaust valve represented generally by the reference numeral 64. The flow of fluid 10 through this outlet or exhaust valve is controlled by a valve member 66 normally tending to move to closed position against its seat under the influence of a spring 67. Said valve member is normally maintained 15 in open position away from its seat, however, by a maintaining means provided therefor, a description of which will later appear. Connected to the discharge side of this outlet or exhaust valve casing is one end of a pipe 70 having its other end connected to a fitting 71, Fig. 2, to which fitting is also connected a pipe 72 leading to any suitable discharge source. 20 When it is desired to open the press, the inlet valve is closed and the outlet or exhaust valve is opened. The steam or the air in the cylinder 30 can then escape therefrom through the conduit means just described 25 and the press is opened by the springs 8, said springs holding the press open until the control mechanism is operated to effect opening of the inlet valve and closing of the outlet or exhaust valve. 30 In order to safeguard the operator of the press from having one or both of her hands caught and crushed between the pressing members by the closing of the press, the present control mechanism requires for its 35 operation to effect closing of the press the use of both of the operator's hands. The use of one of her hands is needed for the operation of the inlet valve and the use of her other hand is needed for the operation of the 40 outlet or exhaust valve. The use of both hands is required until the pressing members have been brought into engagement or substantially so, after which liability of injury to her hands is past and she is then free 45 for other duties or for other things, such freedom being due to the provision of the inlet valve maintaining means hereinafter described. 50 In the present embodiment of the invention, the inlet valve 42 is arranged on the right side of the machine for operation by the right hand of the operator and the outlet or exhaust valve 64 is arranged on the left side of the machine for operation by the operator's left hand. The operating means for the inlet valve includes a hand lever 80 pivoted at 81 to a bracket 82 carried by a bracket 83 secured to the right side of the machine frame and supporting the right 55 side of a work supporting table 84. Said hand lever is provided with a depending arm 85 to the lower end of which is connected a clevis 86 in turn connected to the forward end of a rod 87 having its rear end connected to a pin 88 carried by the upper end of a lever 89 forming a part of the valve interlock hereinafter described. Also connected to the pin 88 of lever 89 is the forward end of a rod 92 having its rear end connected to a clevis 93 in turn connected at 94 to a valve operating lever 95. An extension 96 of said lever is pivoted at 97 to the casing 41 of the inlet valve 42 and is connected at 99 to the upper end of the operating stem 100 for the valve member 43 of the inlet valve. 60 By pushing downwardly on the button 80a of the inlet hand lever 80, rods 87 and 92 and clevises 86 and 93 are moved rearwardly and the valve operating lever 95 with its extension 96 are moved in a clockwise direction 65 about their pivot 97, Figs. 1, 5 and 6, (in a counter-clockwise direction as viewed in Fig. 3). Such movement causes the link 98 connected to the lever extension 96 to move the valve stem 100 downwardly, thereby moving 70 the valve member 43 of the inlet valve away from its seat and permitting fluid to flow through said valve. Communication is thus established between the fluid supply pipe 40 and the cylinder 30 so that fluid can be delivered to said cylinder for the closing and work pressing operation. By regulating the needle valve 46, the flow of fluid therethrough can be controlled, and either fast or slow 75 press closing operations obtained, as will be readily understood. 80 The operating means for the outlet valve is quite similar to the previously described operating means for the inlet valve. In other words, the outlet valve operating means includes a hand lever 105 pivoted at 106 to a bracket 107 carried by a bracket 108 secured to the left side of the machine frame and supporting the left side of the work supporting table 84. Said hand lever 105 is provided with a depending arm 109 to which is connected a clevis 110 in turn connected to the forward end of a rod 111 having its rear end connected to a pin 115 carried by the upper end of a lever 116 forming a part of the valve interlock before referred to and hereinafter fully described. Said pin 115 extends through a slot 117 in a link 118 connected to the forward end of a rod 120 having 90 its rear end connected to a clevis 121 in turn connected at 122 to a valve operating lever 125. The purpose of the lost motion connection between rods 111 and 120 will later appear. An extension 126 of said lever is pivoted at 127 to the casing 63 of the outlet or exhaust valve 64 and is connected to the lower end of a link 130 having its upper end connected at 131 to the upper end of the operating stem 132 for the valve member 66 of the outlet or exhaust valve. 95

By pushing downwardly on the button 105a of the outlet hand lever 105, rods 111 and 120, link 118 and clevises 110 and 121 are moved rearwardly and the valve operating lever 125 with its extension 126 are moved in a counter-clockwise direction about their pivot 127, Figs. 2, 8 and 9, (in a clockwise direction as viewed in Fig. 3). Such movement causes the link 130 connected to the lever 10 extension 126 to move the valve stem 132 upwardly, thereby moving the valve member 66 of the outlet or exhaust valve against its seat and preventing the flow of fluid through said valve. When said valve is closed, the 15 fluid supplied to the cylinder 30 cannot escape or be exhausted therefrom.

As before mentioned, the inlet valve 42 and the outlet or exhaust valve 64 both have a normal tendency to close. In order to hold 20 the outlet or exhaust valve open when the press is open, maintaining means is provided therefor. The maintaining means here shown for this purpose is of mechanical character and includes a sleeve 175 having 25 its lower end connected at 176 to the upper end of the outlet valve operating lever 125. Slidably mounted in the upper portion of said sleeve is a rod 177 provided at its lower end with a head 178, and arranged in the lower portion of said sleeve between said head 178 and the bottom wall 179 of the sleeve is a spring 180. The upper and outer end of rod 177 is connected to a clevis 182 having 30 its upper end pivoted at 183 to an arm 184 secured to and movable with the rear end portion of the head lever 6. When the press is open, as in Fig. 2 and 8, the rod 177 is in lowered position and the spring 180 in sleeve 175 is compressed. When strengthened by 35 such compression, the spring 180 is stronger than the spring 67 which normally tends to close the outlet or exhaust valve, so that said valve is held open by spring 180. When the press is closed, the rod 177 is raised, since it 40 moves with the rear end portion of the head lever 6, and the spring 180 is no longer compressed but has merely its normal strength. Spring 67 is now stronger than spring 180 and spring 67 now serves to maintain the outlet or exhaust valve closed. Spring 67 does 45 not become stronger than spring 180, however, until the pressing members have been brought into engagement, or substantially so, for until such engagement occurs, the rod 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

things, said maintaining means being not effective, however, until after the pressing members have been brought into engagement or substantially so. The maintaining means for the inlet valve includes a sleeve 190 having its lower end pivoted at 191 to the upper end of the inlet valve operating lever 95. Slidably in the upper portion of said sleeve is a rod 192 provided at its lower end with a head 193 and having its upper end connected to a clevis 194 pivoted at 195 to an arm 196 connected to and movable with the rear end portion of the head lever 6. Surrounding the lower end portion of rod 192 and arranged between the head 193 thereof and the upper end 199 of said sleeve is a spring 200. When the operating means for the inlet valve is actuated to effect opening of said valve, the operating lever 95 for said valve turns in a clockwise direction, Figs. 1, 5, 6 and 7, and the sleeve 190 connected thereto is raised, as indicated in Fig. 6. During closing of the press, the rod 192 moves upwardly with the rear end portion of the head lever 6, and when the pressing members have been brought into engagement, said rod has been moved upwardly a sufficient amount to yieldingly hold said sleeve in the position to which it has been raised, as indicated in Fig. 7. The inlet valve is thus held open for the 95 pressing operation.

The operator, therefore, to effect closing of the press, is compelled to manually hold the inlet valve open and the outlet or exhaust valve closed until the pressing members have been brought into engagement, after which the inlet valve maintaining means becomes effective to hold the inlet valve open and the outlet or exhaust valve is held closed by its spring 67. The operator is thus freed for other duties or for other things after there is no longer any liability of injury to her hands by being caught and crushed between the pressing members during closing of the press. When the operating means for the outlet or exhaust valve is actuated to effect opening of the press, as hereinafter described, the inlet valve is closed and remains so, since it is a normally closed valve. The outlet or exhaust valve is opened and it remains so due to the maintaining means provided therefor, the closing tendency of its spring 67 being overcome by the spring 180 of the maintaining means.

If the operator holds the outlet or exhaust valve closed but releases the inlet valve hand lever 80 before engagement of the pressing members has been brought about (and hence before the inlet valve maintaining means becomes effective), the supply of fluid to cylinder 30 will be cut off and the upper pressing member will stop in the position in which it then is. If the inlet valve is kept open but the operator releases the outlet or exhaust valve hand lever 105 before engagement of 130

Similar but separate maintaining means is provided for holding the inlet valve open during the pressing operation, thereby freeing the operator for other duties or other 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

the pressing members has been brought about (and hence before the outlet valve maintaining means becomes ineffective) then the fluid in cylinder 30 will be exhausted therefrom 5 and the press will be fully opened by springs 8.

Depression of the inlet hand lever 80 will effect opening of the inlet valve 42 and fluid will be supplied to the cylinder 30. If, however, the outlet hand lever 105 is not depressed to effect closing of the outlet or exhaust valve 64, said outlet valve will remain open and the fluid delivered to the cylinder 30 will 10 freely escape therefrom through said valve 15 and closing of the press will not be brought about. If the outlet hand lever 105 were to be depressed and the outlet or exhaust valve 64 thereby closed, and the inlet valve 42 not opened by depression of its hand lever 80, then the press would not be closed for no 20 fluid would be supplied to the cylinder 30 for operation of the piston 32 therein. It is therefore necessary to depress both of the hand levers 80 and 105 to effect closing of the 25 press.

If the inlet valve were to leak, then it would be possible to effect closing of the press by depression of the hand lever 105 to close the outlet or exhaust valve, leaving the right 30 hand of the operator free, with consequent liability of injury thereto by being caught and crushed between the pressing members as the press is closed. In order to absolutely 35 safeguard the operator, means is provided for requiring opening operation of the inlet valve before closing operation of the outlet or exhaust valve can be effected, thereby making it necessary to first operate the inlet valve, even though it is leaking.

40 The means provided for this purpose is a valve interlock and includes a latch member 140 having its rear end pivoted at 141 to a bracket 142 secured to the left side of the machine frame. Said latch member is provided on the lower side of its free or front 45 end with a notch 144 to receive a roller 145 carried by the upper end of the lever 116 before referred to, such as by being mounted on one end of the pin 115 of said lever. Said 50 lever 116 has its lower end loosely mounted on the left end of a shaft 147 extending transversely through and journaled in the rear arm 4 of the machine frame, as best shown in Fig. 4. The right end of said shaft has 55 pinned or otherwise rigidly connected thereto the lower end of lever 89, the pin 88 of which, at the upper end thereof, is connected to the rods 87 and 93 of the inlet valve operating means. The latch member 140 is actuated to 60 elevate its free end from engagement with the roller 145 of lever 116 by an arm 152 having its lower end pinned or otherwise rigidly secured to the transverse shaft 147.

When the press is open, the latch member 65 140 is in lowered position and the roller 145

of lever 116 lies within the notch 144 of said latch member, as indicated in full lines, Fig. 8. Inasmuch as the rod 111 of the outlet valve operating means is directly connected to lever 116, movement of said rod 70 and hence depression of the hand lever 105 is now impossible, since lever 116 is latched against movement. To actuate the operating means for the outlet or exhaust valve, it is first necessary to actuate the operating means 75 for the inlet valve, to release latch 140 and thereby release for actuation the outlet valve operating means.

As before mentioned, depression of the hand lever 80 of the inlet valve operating means moves the rod 87 rearwardly, and since said rod is connected to lever 89 by pin 88, rearward movement of said rod causes clockwise movement of said lever. Since lever 89 is fast on shaft 147, clockwise movement of said lever causes corresponding movement of said shaft and corresponding clockwise movement of the arm 152 fast thereon. When the arm 152 is moved in such clockwise direction, its upper end engages and elevates the 80 free end of the latch member 140, thereby freeing its notch 144 from engagement with the roller 145 of lever 116. The operating means for the outlet or exhaust valve can now be actuated, since movement of lever 85 116, and hence rods 111 and 120, is now possible. The position of the latch member 140 after it has been elevated to non-latching 90 position by actuation of the inlet valve operating means but before actuation of the outlet valve operating means is shown in dot-dash lines, Fig. 8. Fig. 9 shows the position 95 of the latch member after actuation of the outlet valve operating means to close said valve.

When the press is open, the pin 115 of lever 116 lies at the forward end of the slot 117 in the link 118 connected to rod 120 of the outlet valve operating means. When the hand lever 105 is depressed to effect closing 100 of the outlet or exhaust valve, the lost motion in this pin and slot connection must be taken up, since in order to move the rod 120 rearwardly, the pin 115 of lever 116 must be moved to the rear end of slot 117. The 105 purpose of this lost motion connection is to effect closing of the inlet valve prior to the opening of the outlet or exhaust valve when it is desired to open the press.

To open the press, the operator with her left hand raises the hand lever 105 of the outlet valve operating means, causing the rod 111 and the lever 116 connected thereto to be moved forwardly. Since the pin 115 of said lever is at the rear end of slot 117, initial forward movement of lever 116 does not produce any movement of rod 120 and hence does not actuate valve lever 125 to open the outlet or exhaust valve. Such initial movement of lever 116 does, however, 110 115 120 125 130

cause its roller 145 to engage and turn in a clockwise direction, Figs. 8, 9 and 10, the latch operating arm 152. Such clockwise movement of said arm causes corresponding movement of shaft 147 to which said lever is pinned, and corresponding clockwise movement of lever 89 also fast on said shaft. Inasmuch as lever 89 is directly connected to rods 87 and 92 of the inlet valve operating means, such clockwise movement of lever 89 produces forward movement of said rods and hence effects actuation of the inlet valve operating lever 95 to produce closing of the inlet valve. By the time the inlet valve is closed, the pin 115 of lever 116 has reached the forward end of slot 117, and further clockwise movement of lever 116 produced by the operator raising the hand lever 105 and drawing forwardly rod 111, pulls the rod 120 forwardly and effects actuation of the outlet valve operating lever 125 to effect opening of the exhaust valve. The press is now free to be opened by the springs 8, since the inlet valve has been closed and the outlet valve 25 has been opened. Such sequential operation of the valve prevents loss or escape of steam or air, as will be readily understood.

In order to cause the movable pressing member 7 to move uniformly down into 30 pressing engagement with the stationary pressing member 3, and to prevent said movable pressing member from moving away from the stationary pressing member and coming to rest with a shock or jar, there extends from the cylinder 30 piping 205 leading to a needle valve 206. Connected to this needle valve is piping 208 leading to the fitting 71 to which is connected the exhaust conduit 72. This needle valve 206 is adjusted 35 to so restrict the escape of air from the lower end of cylinder 30 during the closing of the press as to produce a snubbing action which causes the movable pressing member to move uniformly into pressing engagement with the stationary pressing member 3. When the air is being exhausted from the upper end 40 of the cylinder 30, in the opening of the press, air will be drawn into the lower end of cylinder 30 through the piping 208, the needle valve 206 and the piping 205, causing 45 a snubbing action to take place which prevents the press from opening with a sudden shock or jar, all as will be readily understood.

55 Having described my invention, what I claim is:

1. A pressing machine, comprising relatively movable pressing members, means for effecting engagement and disengagement of 50 said pressing members to thereby close and open the press and including a piston and cylinder structure, and mechanism for controlling the flow of fluid to and from said piston and cylinder structure and including an inlet valve and an outlet valve, means nor-

mally causing said outlet valve to close, and means for automatically maintaining said outlet valve open when the press is open.

2. A pressing machine, comprising relatively movable pressing members, means for effecting engagement and disengagement of 70 said pressing members to thereby close and open the press and including a piston and cylinder structure, and mechanism for controlling the flow of fluid to and from said piston and cylinder structure and including an inlet valve and an outlet valve, means normally causing said outlet valve to close, and mechanical means for automatically maintaining said outlet valve open when the press is open, said maintaining means being operated by opening movement of the press.

3. A pressing machine, comprising relatively movable pressing members, means for effecting engagement and disengagement of 75 said pressing members to thereby close and open the press and including a piston and cylinder structure, and mechanism for controlling the flow of fluid to and from said piston and cylinder structure and including an inlet valve and an outlet valve, said outlet valve normally tending to close under the influence of a spring, and means for automatically maintaining said outlet valve open when the press is open, said maintaining means including spring means having greater strength than said valve closing spring only when the press is open, whereby said outlet valve will be held open by said maintaining means when the press is open.

4. A pressing machine, comprising relatively movable pressing members, means for effecting engagement and disengagement of 90 said pressing members to thereby close and open the press and including a piston and cylinder structure, and mechanism for controlling the flow of fluid to and from said piston and cylinder structure and including an inlet valve and an outlet valve, said outlet valve normally tending to close under the influence of a spring, and means for automatically maintaining said outlet valve open when the press is open, said maintaining means including spring means having greater strength than said valve closing spring only when the press is open, whereby said outlet valve will be held open by said maintaining means when the press is open.

5. A pressing machine, comprising relatively movable pressing members, means for effecting engagement and disengagement of 95 said pressing members to thereby close and open the press, a device having a controlling effect upon said means and having an operative position and an inoperative position, and means for automatically maintaining said device in one of said positions, said maintaining means including a sleeve connected to said device and provided with a coiled spring 100 therein, and a member movable in said sleeve 105

for compressing said spring and connected to and movable with a part movable during relative movement of said pressing members, the compression of said spring enabling the maintaining means to hold said device in such one position.

6. A pressing machine, comprising relatively movable pressing members, means for effecting engagement and disengagement of said pressing members to thereby close and open the press, a device having a controlling effect upon said means and having an operative position and an inoperative position, said device having a spring normally tending to move said device to one of said positions, and means for automatically maintaining said device in said other position, said maintaining means including a sleeve connected to said device and provided with a coiled spring therein, and a member movable in said sleeve for compressing said spring and connected to and movable with a part movable during relative movement of said pressing members, the compression of said maintaining spring rendering it stronger than the spring of said device, whereby upon compression of said maintaining spring the maintaining means holds said device in said other position.

7. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including a normally closed outlet valve, and means for automatically maintaining said valve open when the press is open, said maintaining means being effective to bring about opening of said valve until said pressing members have been brought into engagement.

8. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet valve and an outlet valve, and separate mechanical maintaining means for said valves, said maintaining means being independently operable.

9. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including two valves, and separate maintaining means for said valves, one of said maintaining

means being ineffective when the other maintaining means is effective.

10. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet valve and an outlet valve, and separate maintaining means for said valves, the maintaining means for the inlet valve being ineffective when the maintaining means for the outlet valve is effective.

11. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure, and including an inlet valve and an outlet valve, and separate maintaining means for said valves, the maintaining means for the inlet valve being ineffective when the press is open but effective when the press is closed and the maintaining means for the outlet valve being effective when the press is open but ineffective when the press is closed.

12. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including two valves, and means for preventing actuation of one of said valves until after the other valve has been actuated.

13. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet valve and an outlet valve, and means for preventing the actuation of said outlet valve until after said inlet valve has been actuated.

14. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet valve and an outlet valve, and means for preventing the closing of said outlet

valve until after said inlet valve has been opened.

15. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including two valves, and means for latching one of said valves against operation when the press is open, said latch means being releasable by actuation of the other valve.

16. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet valve and an outlet valve, and means for latching the outlet valve open when the press is open, said latch means being releasable by closing of the inlet valve.

17. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet and an outlet valve, said inlet valve being operable independently of said outlet valve, and means for effecting operation of both of said valves by the operation of one.

18. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet and an outlet valve, said inlet valve being operable independently of said outlet valve, and means for effecting the closing of one of said valves and the opening of the other by the operation of one.

19. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet and an outlet valve, said inlet valve being operable independently of said outlet valve, and means for effecting the closing of the inlet valve by opening operation of the outlet valve.

20. A pressing machine, comprising rela-

tively movable pressing members, means for effecting engagement and disengagement of said pressing members to thereby close and open the press and including a piston and cylinder structure, and mechanism for controlling the flow of fluid to and from said piston and cylinder structure and including an inlet and an outlet valve, means for effecting the closing of the inlet valve by opening operation of the outlet valve, and means for effecting the closing of said inlet valve prior to the opening of said outlet valve.

21. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet and an outlet valve, operating means for said inlet valve, operating means for said outlet valve, means for interlocking said valve operating means so as to effect actuation of the inlet valve operating means to effect closing of said valve by the actuation of the outlet valve operating means to effect opening of the outlet valve, and a lost motion connection in the operating means for said outlet valve for effecting the closing of the inlet valve prior to the opening of the outlet valve.

22. A pressing machine, comprising relatively movable pressing members, means for effecting engagement and disengagement of said pressing members to thereby close and open the press and including a piston and cylinder structure, and mechanism for controlling the flow of fluid to and from said piston and cylinder structure and including an inlet valve and an outlet valve, latch means for holding said outlet valve against operation when the press is open, and means for interlocking said valves so as to effect the release of said latch by operation of said inlet valve and for effecting, when the press is closed, the closing of said inlet valve by opening operation of said outlet valve.

23. A pressing machine, comprising relatively movable pressing members, means including a pair of valves for effecting engagement and disengagement of said pressing members to thereby close and open the press, and mechanism for controlling the operation of said means and including two valve controlling members, one for each valve, for actuation by the operator, and means for preventing the actuation of one of said valve controlling members until after the other valve controlling member has been actuated.

24. A pressing machine, comprising relatively movable pressing members, means for effecting engagement and disengagement of said pressing members to thereby close and open the press and including an inlet valve,

and an outlet valve, and mechanism for controlling the operation of said means and including two valve controlling members for actuation by the operator, there being a controlling member for the inlet valve and a controlling member for the outlet valve, and means for preventing the actuation of the outlet valve controlling member until after the inlet valve controlling member has been 10 actuated.

In testimony whereof I hereby affix my signature.

ROBERT C. PAULY.
